UNITED STATES PATENT OFFICE.

ELMER G. LEON, OF HUBLETON, WISCONSIN.

AUTOMATIC SAFE-CLOSER.

1,348,017.

Specification of Letters Patent.

Patented July 27, 1920.

Application filed January 5, 1920. Serial No. 349,421.

To all whom it may concern:

Be it known that I, ELMER G. LEON, a citizen of the United States, residing at Hubbleton, in the county of Jefferson and State 5 of Wisconsin, have invented new and useful Improvements in Automatic Safe-Closers, of which the following is a specification.

This invention relates to safety devices for banks or other institutions using safes 10 and has for its object the provision of a device associated with the handle of the door of a time lock safe whereby upon closing of a switch, such as a foot push button, the safe door will be locked to prevent access thereto by robbers.

Another object is the provision of a device of this character in which the member connected with the safe door is under spring tension which is released by the closing of 20 the circuit through an electro-magnet controlling the position of a trigger.

A further object is the provision of a device of this character so constructed that liability of its being set off by accident will 25 be reduced to the minimum.

An additional object is the provision of a device of this character which will be comparatively simple and inexpensive in manufacture and installation, highly efficient in 30 use, durable in service, and a general improvement in the art.

With the above and other objects and advantages in view the invention consists in the details of construction to be hereinafter 35 more fully described and claimed and illustrated in the accompanying drawings in which.

Figure 1 is a face view of a safe showing my device associated therewith and showing 40 the wiring connections.

Fig. 2 is a plan view of my device in set position,

Fig. 3 is a similar view in released position,

Fig. 4 is a cross sectional view taken 45 through the trigger mechanism,

Fig. 5 is a side elevation of the device on a larger scale than Fig. 1, and

Fig. 6 is a detail cross sectional view 50 showing the mounting of the spring-pressed actuating arm,

Fig. 7 is a perspective view of these parts detached,

Fig. 8 is a perspective view of the armature, and

Fig. 9 is a perspective view of the trigger.

Referring more particularly to the drawings; the letter A designates a time lock safe, B designates the door thereof, and C designates the closing handle.

In carrying out my invention I provide a supporting base 10 which may be in the nature of an elongated wooden block, though it will be apparent that some other suitable structure might be provided. Secured centrally upon this base is a bracket 11 having bearing ears 12 through which is journaled a spindle 13 surrounded by a coil spring 14 which has one end engaging the bracket and its other end engaged within a slot 15 in the end of the spindle. The other end of this spindle is squared, as shown at 16, and has secured thereon, as by means of a suitable set-screw 17, an arm 18, the terminal of which carries a ring 19.

Connected with this ring 19 is a spring 20 to which is connected a chain 21 which leads to the safe and which carries at its free end a ring 22 engageable over the handle C of the safe door.

Located within a suitable recess 23 in the base 10 is an electro-magnet 24 with which is associated an armature 25 carried by the arm 26 pivoted, as at 27, upon a bracket 28. The arm 26 has formed thereon a right 25 angularly extending portion 29 having its free edge provided with a lip 30. Pivoted upon the base, as shown at 31, is a trigger bar 32 which has its free end engageable beneath the lip 30.

In the installation of the device, use is made of any desired number of switches in the form of floor push buttons 33 and use is also made of an elevated wire 34 which extends across the room in which the device is located and which is connected with a suitable switch 35. The push buttons 33 and the switch 35 are interposed in circuit with the electro-magnet 24 and a suitable source of current 36.

In the operation of the device the operator grasps the arm 18 and rotates it against the resistance of the spring 14 so that it will lie upon the base 10 beneath the trigger 32, it being understood of course that the trigger must be initially swung out of the way. After the arm 18 is thus disposed the trigger 32 is swung to extend over the arm and has its free end engaged beneath the lip 30 on the armature arm 26. It should be here stated that I preferably provide a sheet metal shield 37 which extends from the

electro-magnet and its associated parts for protecting the electro-magnet and trigger. The parts being thus set, the ring 22 on the end of the chain 21 is engaged over the handle C of the safe, it being understood that the time locks on the safe must be set and the handle moved to such position that the lugs on the door will just clear.

In the event of a hold-up when the bank employees are required to "throw up their hands" it is intended that any employee near the wire 34 should grasp the same and exert a pull thereon to close the switch 35, or else step on one of the push buttons 33. In either event the result will be to close the circuit through the electro-magnet 24 and the consequent energization of the magnet will result in attraction of the armature 25 which will cause the lip 30 on the arm 26 to be moved out of engagement with the trigger 32. The tension of the spring 14 will then swing the arm 18 and this will result in pulling upon the chain 21 which will slam the door and move the handle C to locked position. It will thus be apparent that the safe will be protected from robbery as the time locks thereon cannot be released until the time limit has expired. As safe doors are of different weights it is necessary that in some instances the tension of the spring 14 be greater than in other instances. My device provides for adjustment in this particular as the arm 18 may be removed, a screw-driver engaged within the slot 15 and the spindle rotated and the arm 18 then re-engaged thereon.

From the foregoing description and a study of the drawings it will be apparent that I have thus provided a simple and easily set device which will efficiently pro-

tect a safe against robbery. It will be observed that by placing the various push buttons at many places it will be possible to lock the safe from most any location.

While I have shown and described the preferred embodiment of my invention, it is of course to be understood that I reserve the right to make such changes in the form, construction, and arrangement of parts as will not depart from the spirit of the invention or the scope of the subjoined claims.

Having thus described my invention, I claim:

1. In combination with the handle of a time lock safe door, an automatic door closing device comprising a spring-pressed arm, a flexible member connected with the arm and with the door handle, a trigger member engaging over said arm and normally maintaining the same under tension, a lever engaging said trigger member for holding the same in operative position, and electro-magnetic means for moving said lever out of engagement with said trigger.

2. In combination with the handle of a time lock safe door, a spring-pressed arm connected with the handle, an electro-magnet, a lever pivoted adjacent the electro-magnet and carrying an armature disposed over the cores thereof, and a trigger bar engaging said lever and said arm and normally holding said arm under tension, said electro-magnets being in circuit with a source of current and a circuit closer whereby upon closing of the circuit the lever will be moved to release said trigger member whereby said arm will swing to close the door.

In testimony whereof I affix my signature.
ELMER G. LEON.
